ATTACHMENT BRACKET MEANS FOR ATTACHING BED SPRING MEANS TO A HEADBOARD AND A FOOTBOARD TO FORM A BED

Robert R. Vail, Altadena, Calif., assignor of one-tenth to Gadget-Of-The-Month Club, Inc., North Hollywood, Calif., a corporation of California

Filed Mar. 30, 1959, Ser. No. 802,946

2 Claims. (Cl. 5—288)

The present invention consists of attachment bracket means for attaching bed spring means to a head board and a footboard to form a bed, the complete combination consisting of headboard, footboard, bed spring means, and four attachment brackets comprising an assembled bed in accordance with the present invention, and, as a subcombination, one of the attachment brackets, per se, adapted for the uses set forth above.

It is customary for a baby to be provided with a crib having a high headboard, a high footboard, and two high side retaining walls which are usually slatted, and with one of said side walls in certain instances being of the controllably vertically adjustable and lockable type, although not all cribs are so constructed. The reason why the conventional baby crib has such high surrounding walls is, of course, to protect the baby from accidentally rolling out of bed at night or of getting out of bed of his own volition when awake. However, after a baby has used such a crib for a number of years, the high sides are actually no longer necessary and may even interfere with the convenient making of the bed by removing, cleaning, and repositioning mattress, pad, sheets, blankets, and the like, and, furthermore, may make it more difficult to use the crib easily and conveniently. In other words, after the necessity of positively retaining the very young baby in the crib by means of the high sidewalls, has passed, the necessity for the high side walls is also no longer present, and the baby bed would be substantially improved if the crib sidewalls could be removed. However, in conventional baby cribs, this is not possible because the sides of the conventional baby crib act to keep the headboard and footboard in an upright position and the bed spring means and mattress just hook onto them. Therefore, if the sides of a conventional baby crib were removed, the remaining structure would not stand up and would be unusable.

In view of the above, the present invention was developed for the purpose of solving this problem and making it possible to remove the sides from a conventional crib and to fasten opposite end corners of the frame of a conventional baby bed spring means to the headboard and also to the footboard at four rectangularly spaced locations, as seen in plan view, whereby to effectively form a complete baby bed having no sides and thus being much more convenient for a small child to use and also more convenient for his mother in changing the bed linen, etc.

It should be noted that the crib headboard and footboard may be reused along with the crib bed spring means through the use of four of the attachment bracket means of the present invention. However, other suitable headboards and footboards may be used, if desired, with the conventional crib bed spring means.

It is an object of the present invention to provide a complete baby bed or child's bed formed by fastening four attachment bracket means to four side corner portions of bed spring means and fastening two of said attachment bracket means to a headboard and two of said at-

2

achment means to a footboard whereby to comprise a structurally strong complete child's bed structure having no sides.

It is a further object to provide apparatus of the character set forth in the preceding object, wherein the headboard, the footboard, and the bed spring means may all comprise portions of a pre-existing conventional baby crib which has had its sides removed and which has had the four attachment bracket means added to the combination structure to produce a complete structurally strong child's bed having no sides.

It is a further object to provide a new and novel attachment bracket of the type embodied in the two preceding objects, adapted for engaging a portion of a bed spring means adjacent a corner thereof and also provided with controllably operable fastening means adapted to engage a vertically directed end member, such as a headboard or footboard of a bed.

It is a further object to provide an attachment bracket of the character set forth in the preceding object, and also a complete combination structurally strong baby bed having no sides of the character referred to in several of the preceding objects, which are of extremely simple, cheap, foolproof construction such as to be conducive to widespread use thereof.

Further objects will be apparent to persons skilled in the art after a careful study hereof.

For the purpose of clarifying the nature of the present invention, two exemplary embodiments are illustrated in the hereinbelow-described figures of the accompanying single sheet of drawings, and are described in detail hereinafter.

Fig. 1 is a reduced-size perspective view of one exemplary embodiment of the complete combination form of the invention, wherein four attachment brackets in accordance with the present invention are attached to four side corner portions of the frame of bed spring means to effectively mount same with respect to an opposed headboard and footboard whereby to produce a structurally strong complete baby bed having no side walls.

Fig. 2 is a larger-scale fragmentary view of one illustrative bracket means of the present invention in engaged relationship with a fragmentary portion of one side corner of the frame of the bed spring means shown in Fig. 1.

Fig. 3 is an enlarged fragmentary view, partly in elevation and partly in vertical section, taken in the direction of the arrows 3—3 of Fig. 4.

Fig. 4 is an enlarged fragmentary view, partly in elevation and partly in vertical section, taken in the direction of the arrows 4—4 of Fig. 3.

Fig. 5 is an enlarged side elevational view of a slightly modified form of the horizontal flange-engaging portion of the fastening clamp means for locking the attachment bracket to a portion of the frame of the bed spring means.

Fig. 6 is a view similar to Fig. 5 but shows the modified form of the horizontal flange-engaging portion in vertical section.

The complete combination form of the present invention may be said to comprise a structurally strong baby bed having no sidewalls, and being formed of conventional bed spring means having engaged therewith adjacent each of the four corners thereof, attachment bracket means, two of which, at each end of the bed spring means, in turn being fastened to a headboard or footboard, and vice versa, at the other end of the bed spring means.

In the specific embodiment illustrated in Figs. 1—4, the above-mentioned bed spring means takes one specific form, indicated generally at 10, wherein it consists of a substantially rectangular frame 11 of substantially L-shaped cross-sectional configuration having substantially vertical downwardly directed first flange means 12 and

substantially horizontal inwardly directed second flange means 13, and being provided with and interconnected by a plurality of reticulated intersecting interconnected resilient members 14, which effectively act as springs adapted to resiliently support a mattress, such as that indicated generally at 15 and which is shown in rolled-back position in order to clarify the disclosure.

In the specific example illustrated, two of the above-mentioned vertically directed end members are included and comprise a headboard 16 and a footboard 17, each of which is effectively connected to the side end portions of the frame 11 of the bed spring means 10 in the manner clearly shown underneath the rolled-back portion of the mattress 15 and at the most remote end corners of the bed spring means 10 shown in Fig. 1, by suitable attachment bracket means, such as are indicated generally at 18.

In the specific example illustrated, each of the four attachment bracket means 18 (three of which are shown in Fig. 1 and the other one of which is similarly but oppositely connected to the footboard 17 and the far side and end corner of the frame 10) takes a specific form wherein it comprises a longitudinal upwardly open U-shaped vertical flange-receiving member 19 of U-shaped cross-sectional configuration adapted to receive downwardly therein the corresponding portion of the vertical downwardly directed first flange means 12 of the frame 11 of the bed spring means 10 adjacent a corner thereof, whereby to effectively longitudinally support the vertical flange 12 of the frame 11 along a portion of the length thereof. Also, in the specific example illustrated, each of the vertical flange-receiving members 19 is provided at the bottom thereof with upwardly and inwardly directed controllably adjustable and lockable fastening clamp means, such as indicated generally at 20, having an inwardly and upwardly displaced horizontal flange-engaging portion, such as indicated at 21, adapted to tightly engage the top of the substantially horizontal inwardly directed second flange means 13 of the frame 11 of the bed spring means 10 for tightly drawing together said vertical flange-receiving member 19 and the frame 11 of the bed spring means 10. This is accomplished by means of the threaded fastener or bolt member 22 having a head 23 positioned in an apertured portion 24 formed out of or struck out of the bottom of the vertical flange-receiving member 19, with said threaded bolt or fastener 22 having its other end extending upwardly and inwardly through an aperture in the horizontal flange-engaging portion 21 and being longitudinally adjustably fastened with respect thereto by interiorly threaded nut means 25, whereby the entire clamp means indicated generally at 20 may be tightened so as to tightly clamp the U-shaped vertical flange-receiving member 19 to the frame 13 adjacent the corners thereof in the manner clearly shown in Figs. 2-4.

In the specific example illustrated, one end of the vertical flange-receiving member 19 is provided with a transversely directed fastening plate, such as is indicated at 26, and fastening means comprising the apertures 27 and the fastening screws 28 carried thereby for effectively controllably fastening the entire attachment bracket 18 to a portion indicated at 29 in Figs. 1, 3, and 4, of the headboard 16 and also the footboard 17 whereby to form a firm rigid structure comprising the headboard 16, the footboard 17, the bed spring means 10, and the four attachment brackets 18.

Figs. 5 and 6 illustrate a slight modification of the horizontal flange-engaging portion 21 and the fastening nut 25, best seen in Fig. 3, and in this modification similar parts are indicated by similar reference numerals, primed, however. The modified form of horizontal flange-engaging portion 21' shown in Figs. 5 and 6 has interiorly threaded fastening means 25' equivalent to the threaded fastening nut 25 shown in Fig. 3, but actually formed in and comprising a part of the member 21' in this modification.

It should be noted that the present invention is directed

to a complete combination of the type illustrated in Fig. 1, and also to an individual attachment bracket, per se, of the type illustrated in Figs. 2-4 or as modified in accordance with Figs. 5 and 6, plus any equivalents thereof within the scope of the teachings and disclosure of the present invention.

It should be understood that the figures and the specific description thereof set forth in this application are for the purpose of illustrating the present invention and are not to be construed as limiting the present invention to the precise and detailed specific structure shown in the figures and specifically described hereinbefore. Rather, the real invention is intended to include substantially equivalent constructions embodying the basic teachings and inventive concept of the present invention.

I claim:

- Attachment bracket means for attaching to a vertically directed headboard and a vertically directed footboard opposite side corners of bed spring means, comprising: bed spring means consisting of a substantially rectangular frame of substantially L-shaped cross-sectional configuration having substantially vertical downwardly directed first flange means and substantially horizontal inwardly directed second flange means, and being provided with and interconnected by a plurality of reticulated intersecting resilient mattress supporting members; a vertically directed headboard; a vertically directed footboard; four longitudinal upwardly open vertical flange-receiving members of U-shaped cross-sectional configuration, each removably receiving downwardly therein a different side corner portion of said substantially vertical downwardly directed flange means of said frame of said bed spring means, whereby to effectively longitudinally support said frame along the length thereof at four corner locations, each of said flange-receiving members being provided at the bottom thereof with upwardly and inwardly directed controllably adjustable and lockable fastening clamp means having an inwardly and upwardly displaced horizontal flange-engaging portion adapted to tightly engage the top of a corresponding corner portion of said substantially horizontal inwardly directed second flange means of said bed spring means for tightly drawing together said vertical flange-receiving member and the bed spring frame at each of the four corner portions thereof, each of said controllably adjustable and lockable fastening clamp means including an apertured downwardly and inwardly projecting portion formed out of the bottom of the flange-receiving member, and further including upwardly and inwardly directed threaded fastener means adjustably connected to said horizontal flange-engaging portion, similar ends of two of said vertical flange-receiving members, each being provided with a transversely directed fastening plate and fastening means carried thereby effectively fastening same to said vertically directed headboard at opposite sides thereof, and similar ends of the remaining two of said vertical flange-receiving members each being provided with a transversely directed fastening plate and fastening means carried thereby effectively fastening same to said vertically directed footboard at opposite sides thereof, thereby effectively mounting said bed spring means between said headboard and said footboard.

- An attachment bracket for attaching to a vertically directed end member a side corner portion of a bed spring means of the type consisting of a substantially rectangular frame of substantially L-shaped cross-sectional configuration having substantially vertical downwardly directed first flange means and substantially horizontal inwardly directed second flange means interconnected by a plurality of mattress supporting members, comprising: a longitudinal upwardly open vertical flange-receiving member of U-shaped cross-sectional configuration adapted to receive downwardly therein a portion of a substantially vertical downwardly directed first flange means

of a frame of a bed spring means adjacent a side corner portion thereof, whereby to effectively longitudinally support the vertical flange means of the frame along a portion of the length thereof, said flange-receiving member being provided at the bottom thereof with upwardly and inwardly directed controllably adjustable and lockable fastening clamp means having an inwardly and upwardly displaced horizontal flange-engaging portion adapted to tightly engage the top of a substantially horizontal inwardly directed second flange means of the bed spring means for tightly drawing together said vertical flange-receiving member and the bed spring frame comprised of a first vertically downwardly directed flange means and a second horizontal inwardly directed flange means, said controllably adjustable and lockable fastening clamp means including an apertured downwardly and inwardly projecting portion carried by the bottom of the

vertical flange-receiving member, and further including upwardly and inwardly directed threaded fastener means adjustably connected to said horizontal flange-engaging portion, one end of said vertical flange-receiving member being provided with a transversely directed fastening plate and fastening means carried thereby for effectively controllably fastening same to a vertically directed end member for effectively mounting the bed spring means with respect thereto.
